DATA INPUT-OUTPUT TERMINAL

Melvin Rudin, Palo Alto, Calif., assignor to Datei Corporation, McLean, Va.

Filed Nov. 4, 1970, Ser. No. 25,926

Term of patent 14 years

Int. Cl. D14—02

U.S. Cl. D26—5

FIG. 1 is a front perspective view of a data input-output terminal showing my new design;

FIG. 2 is a rear view thereof;

FIG. 3 is a top plan view thereof;

FIG. 4 is a right side view thereof;

FIG. 5 is a front elevational view thereof; and

FIG. 6 is a left side view thereof.

I claim:

The ornamental design for a data input-output terminal, as shown.
